ABSTRACT OF THE DISCLOSURE

A sand-circulation oven for the continuous heat treatment of ball-shaped products, characterised in that said products are carried through the oven while a material consisting of fine particles, such as sand, is circulated through said products in order to produce a heat transfer between said products and said material.

This invention relates to a sand-circulation oven of the type designed for heating miscellaneous products in the form of balls. The term "ball" is used herein for designating any product in the form of relatively large granules of substantially spherical configuration. The characteristic dimension of these balls may range from $\frac{1}{4}$ " or $\frac{5}{16}$ " to about 4". The granules may result either from the crushing of larger lumps or blocks, or from a ball press or a ball-producing drum or cylinder. On the other hand, the term "sand" denotes herein any desired relatively fine-grained material of a size of, say, less than 0.04".

It is known that a bed of products in ball form, laid upon a grate or grid cannot, retain fine sand deposited on this ball bed. The sand flow is improved if the balls and sand differ considerably in size and if the supporting grid is vibrated.

The oven constituting the subject-matter of the present invention is based on this physical phenomenon and characterised in that the ball-shaped products are submitted to variable accelerations while the fine-grained or sand material is circulated through said balls in order to cause the transfer heat therebetween.

The specific heating method according to this invention is particularly suited for products distilling volatile substances when heated, especially if the pollution and dilution of these volatile substances must be avoided to improve their recovery rate.

According to a specific form of embodiment of this invention an oven of the type set forth hereinabove comprises: a continuous or endless chain mesh-belt or grid, divided into one or several sections disposed horizontally or inclined, to which variable accelerations are impressed, and adapted to carry the ball products; one or a plurality of upper distributors for depositing sand upon the top of the ball bed; means for adjusting the sand circulation rate through said ball bed; a fluidized bed fed with the sand having passed through the ball bed, and means for lifting the sand back into the upper distributor.

According to a specific feature characterising this invention a fluidized loop causes the sand to circulate in counter-current relationship to the ball-shaped products, whereby the heat resulting from the cooling of said balls can be recovered.

According to this invention the oven comprises several zones, namely a preheating zone, a heating zone and a cooling zone, and each zone is adapted to recycle the sand from the fluidized channel. This channel extends through the combustion chamber and circulates in counter-current relationship with respect to the ball products carried by the grid, the circulation for heat-recovery pur-

2

pose being independent of the sand circulation through the ball charge.

According to a modified form of embodiment the above-defined oven zones are coupled in series, the sand being picked up from the bottom of each zone by a hopper and lifted back to the top distributor or distributors.

The combustion chamber of the oven may operate for example by using burners immersed in the fluidized bed for delivering the heat necessary for heating the charge, 10 a cyclone being provided for exhausting the smoke from the burners. The combustion chamber may advantageously comprise baffle means so arranged in the fluidized bed as to impart changes of direction to the particles whereby the complete particle flow can be heated homogeneously.

The sand may further be heated outside the oven, in an internal-combustion fluidized bed, or in a smoke-flow oven, or in a rotary oven. Furthermore, it can be heated by the ducts used for lifting the particles, these ducts 20 receiving in this case the hot smoke directly from a burner.

According to a specific form of embodiment of the oven according to this invention means are provided for collecting and utilizing, without dilution, or with a metered dilution, the combustible vapors from the distillation process of the ball-shaped products and/or their binder.

Other features and advantages of this invention will appear as the following description proceeds with reference to the attached drawings given by way of illustration, it being understood that many modifications can be brought thereto without departing from the spirit and scope of the invention. In the drawings:

FIGURE 1 is a vertical sectional and elevational view 35 of a typical form of embodiment of an oven according to this invention, the section being taken along the line 1—1 of FIGURE 3;

FIGURE 2 is a plan view of the oven illustrated in FIGURE 1;

FIGURE 3 is a section taken upon the line 3—3 of FIGURE 1;

FIGURE 4 is a section taken along the line 4—4 of FIGURE 2;

FIGURE 5 is a section taken along the line 5—5 of FIGURE 2;

FIGURE 6 is a diagrammatic section showing a typical example of means for lifting the sand back to the upper distributor;

FIGURE 7 is a diagrammatic illustration of a sand circulation path in the oven;

FIGURE 8 illustrates also diagrammatically a typical example of a sand circulation path in the oven; and

FIGURE 9 illustrates diagrammatically a method of recovering fuel vapors from the distillation of the ball products and/or their binder.

Referring to the drawings and more particularly to FIGURES 1 and 2, it will be seen that the ball-shaped products B circulate from left to right as seen in these figures. They are carried by an inclined grid, which may either consist of a single plane or, alternately, of a stepped structure to permit the periodic exposure of different portions of the product and also the loosening of clods. This grid may also be disposed horizontally, if desired. In the example illustrated it consists of a plurality of successive sections 11, 12, 13 and 14. This grid is subjected to variable accelerations obtained for example by using hydraulic actuators or piston-cylinder units 16. The cylinders of these actuators are secured to the frame structure 17 supporting the grids and their piston rods are attached to fixed points, or vice versa. The frame structure 17 of these grids is supported by rollers such as 18, 18' disposed at spaced intervals, externally of the

oven, like the actuators 16. These rollers 18, 18' are provided with shafts rigid with a fixed frame 19 supported by the ground and supporting the installation. The relative spacing of the grid-forming bars is determined with a view to prevent any jamming of the products B. The balls circulating on the top of grids 11 to 14 are retained laterally by vertical side walls 24 and 24'.

The inclination and the accelerations imparted to the grid may be such that products B are free from any frictional contact or shocks with the grids. The frequency and amplitude of the accelerations permit of adjusting the feed rate of the products.

Fixed scrapers having fingers adapted to extend through the grid bars are provided for avoiding any clogging thereof. The fingers 20 of one of these scrapers are illustrated which co-act with the bars of grid 13.

The sand S is discharged upon the top of the ball layer B, throughout the length thereof, from a number of upper distributors such as the one designated by the reference numeral 15 in the drawing. This distributor 15 comprises a fixed upper casing 21 into which an inlet duct 22 discharges sand recovered from the oven, as will be described presently in detail, and an outer sleeve 23 adapted to be adjusted vertically along the distributor axis for altering at will the distance from the bottom of the distributor to the grid, i.e. the height of the natural angle of repose of the sand heap formed above the charge, and therefore for modifying at will the amount of sand dispensed upon the ball bed.

This sand is retained laterally by the walls 24, 24' of the housing supporting the grids, and at either end sand joints 25, 26 are provided for sealing the oven enclosure 27 in which the charge B and the sand S flowing therethrough circulate for producing the desired heat transfer.

The sand circulation output through the charge B is adjustable for example by means of a double series of horizontal plates 28 and 28' disposed at right angles to the direction of flow of the ball products and disposed beneath each grid. These movable plates 28, 28' are adapted to slide on each other and act as diaphragms actuated either manually by means of a handle 29 (FIGURE 3) or by using servo-motor means in order to maintain the temperature of the charge B at a predetermined value.

After having passed through the bed of ball products B the sand falls into a plurality of hoppers such as 30 disposed beneath the grids and adapted to feed a fluidized bed 31. A particle aspirator or trompe is provided at the bottom of each hopper for feeding each upper distributor 15. Each aspirator or trompe consists of two coaxial tubes 32, 33, respectively, capable of directing the sand pneumatically up to the duct 22 feeding the distributor 15. A cyclone or like scrubber 34 is arranged in the distributor for separating completely the particles from the suction air stream delivered via the tube 33.

Means are provided for adjusting the sand level in the upper distributors 15. These means, consisting for example of electric contacts, are disposed in each upper distributor 15 and capable of detecting the upper and lower level of the sand in order to actuate in the "all or none" manner the means supplying fluid to the particle-sucking trompe or aspirator. Any suitable servo device may be used for controlling these means.

The width of the casing limited laterally by the walls 24, 24' corresponds to the width of the grids 11. On the other hand the length of this casing will be selected as a function of the permeability of the charge of ball-shaped products and also of the amount of sand to be circulated.

To improve the distribution of the heating sand over the balls, the bottom of each distributor may consist of a plate 35 formed with louvres, slots or perforations.

According to a modified form of embodiment of this invention, illustrated in FIGURE 6, the sand is recovered in a diluted phase at the bottom of each hopper 30 in a

duct 36 by using a supply of compressed gas 38 fed to the bottom of this duct. An electric switch 37 is provided for discontinuing the supplying of compressed gas when the sand level in hopper 30 is below a predetermined minimum value.

The manner in which the sand circulates from one zone to another zone of the oven will now be described.

The oven illustrated by way of example in the drawings comprises four zones (see FIGURE 7):

A preheating zone Z₁ (corresponding to grid 11).

Two heating zones proper Z₂ and Z₃ (corresponding to grids 12 and 13).

A cooling zone Z₄ (corresponding to grid 14).

In this figure there is illustrated diagrammatically a sand circulation path in the oven.

The ball-shaped products B circulate in the direction of the arrow b after having been introduced at A. A fluidized loop F causes the sand to circulate in counter-current relationship (see arrows s) to the products B, whereby the heat resulting from the cooling of the balls in zone Z₄ can be recovered.

Each zone Z₁ to Z₄ is adapted to recycle the sand from the fluidized channel (fluidized beds 31 of FIGURES 1 to 3). A combustion chamber C described more in details hereinafter and operating for example with immersed burners, will supply the heat required for heating the charge.

The sand arriving at the end of the fluidized loop F flows over a chute and falls into a storage hopper T. This chute permits of maintaining the fluidized bed 31 (FIGURE 1) at a constant level. The function of hopper T is to maintain a certain reserve of sand for operating the plant and also to store the particles when the oven is inoperative or held up for any reason. A suction trompe or aspirator R is dipped into this hopper and feeds the loop inlet. The output of this trompe will regulate the total sand circulation in the loop F. The output should be so adjusted as to ensure the best possible heat recovery, this requirement being met when the heat storage capacity of the sand nearly equals that of the ball products.

If the ball-shaped products require a stronger cooling, the sand in the return channel of the fluidized loop F may be cooled for example by using water or steam piping, or a water vaporization carried out directly within the fluidized bed.

In the example illustrated in FIGURE 7 the recovery circulation is independent of the sand circulation through the charge B. On the other hand, in the alternate form of embodiment of the invention illustrated in FIGURE 8 the four zones Z₁ to Z₄ are coupled in series. The sand picked up from the bottom of each zone by a hopper is lifted by a trompe or aspirator for example of the type shown in FIGURE 6 and to be described presently.

This form of embodiment is more economical but at the expenses of the flexibility of the installation. Of course, it would not constitute a departure from the spirit and scope of the invention to contemplate other modifications, for example, the one consisting in coupling said zones Z₁ to Z₄ by pairs. Moreover, although this specification refers to a four-zone oven, it is clear that the number of zones of the oven may be increased or reduced without departing from the basic principle of the installation constituting the subject-matter of this invention.

Now the method utilized for heating the sand will be described with reference to FIGURES 1 to 5 of the drawing.

The combustion chamber of the oven according to this invention comprises two immersed burners 39 and 40 dipping into the fluidized bed 31.

A cyclone 41 is provided for sucking the smoke from the two burners 39 and 40 and exhausting it to the outside through a vent duct 42. The combustion chamber comprises in the fluidized bed 31 baffle means such as a 70 75 43 adapted to impart to the particles a movement shown

by the arrows of FIGURE 2, in order homogeneously to reheat the flux of these particles.

A larger installation would require, of course, a greater number of burners. Besides, the sand could be heated externally of the oven, without departing from the present invention, by using a fluidized, internal-combustion bed, or a smoke-stream bed, or alternately a rotary oven, but it is clear that these suggestions should not be construed as limiting the invention.

If the sand became more or less smoothed by its contact with the ball-shaped products, one fraction of the sand may be heated at a higher temperature to eliminate the pollution therefrom. This fraction is subsequently mixed with the main mass of sand.

In the oven proper the sand may further be heated by the trompes or aspirators used for lifting the particles (and consisting of the ducts or tubes 32 and 33 shown in FIGURES 3 and 5). In this case the hot smoke from a burner is fed directly to the trompes or aspirators. The combustible fluid and air may then be brought just to the lower end of the trompe which in this case will act itself as a burner.

The oven according to this invention may advantageously be provided with means for recovering gases from processes applied to ball-shaped materials or products. Thus, for example, if the oven is used for reducing the smoke content of coal, or treating agglomerated products in which tar, pitch and/or bitumen is used as a binder, volatile substances are released either from the products themselves, or from their binder or binders. These volatile substances are combustible and consist of a gaseous mixture of hydrogen, CH_4 , etc., and also of tar vesicles or bubbles.

In most of the known plants of this kind these products are lost if they cannot be burned immediately. Besides, particular attention must also be paid to the fact that they cannot be exhausted through the chimney to the atmosphere without raising atmospheric pollution problems.

The advantage of using a sand circulation oven is to prevent the dilution of these combustible vapors, whereby they can become a gas having a high heating power which is easy to burn as such.

FIGURE 9 illustrates diagrammatically the manner in which these combustible vapors can be recovered. These vapors are sucked at 45 and directed into the enclosure 28 (FIGURE 1) by a suction fan 44 (FIGURE 9) through heat-insulated pipe lines 45. At the same time a pressure slightly in excess of the atmospheric value is maintained in the oven chamber 27; a by-pass valve 46 is provided for adjusting the pressure within the oven. The vapors thus discharged through the duct 47 are directed to the burners of this oven, the excess being burned if desired in a near-by boiler.

A slight dilution may promote the extraction of these combustible vapors. In this case a pre-adjusted smoke output will be fed into the oven by means of rows of nozzles provided to this end.

To avoid any ingress of air the oven is sealed by means of bellows such as 48 and 49 disposed at either end thereof (see FIGURES 1 and 2). Moreover, the upper housing of the sand distributor is constantly kept under pressure to prevent the ingress of carrier fluid. The fluidized beds circulate in closed casings.

The fluidizing gas can escape either through orifices such as 50 formed in the outer tube 32 of the trompe, or from the end of the cold channel towards the storage hopper (denoted by the reference letter T in FIGURE 7). On the other hand, the sand column formed at the bottom of each hopper 30 will limit considerably the ingress of fluid.

If the gases released during the process are of combustible nature, the fluidized beds and the trompes are supplied with scrubbed smokes without any oxygen content in order to avoid a detrimental air input likely to develop

detonating mixtures. Moreover, it is clear that the oven constituting the subject matter of this invention can be used for processing products in atmospheres of predetermined composition.

Regarding the specific nature of the products to be treated, the above-described oven is capable of processing all products in the form of balls or granules of such dimensions that sand can flow therethrough. These products may consist for example of ore pellets, agglomerated ores, with or without binder, agglomerated coal for roasting torrefaction, etc.

During the treatment, these products may go through a plastic deformation phase, as in the case of certain coals. In this case it is possible to arrange under one or more metal grids a metal plate preventing any flow of the sand along a predetermined zone length. Thus, the products are maintained without any deformation in a fixed bed. The amount of heat transferred from the sand enables the products to clear the critical temperature.

The nature of the sand will be selected as a function of the oven temperature in order to obtain a satisfactory resistance to this temperature and to erosion. The sand granulometry will be such that it will circulate and flow freely through the charge.

In the case of ore roasting applied to ball-shaped or pellet ore, the ore itself sieved to the proper granulometry may be used as sand. The fines from the oven will be directed to the ball-forming device. In the oven the sand will be sieved before penetrating into the storage hopper in order to eliminate abnormally large granules from the charge.

According to another form of embodiment of the oven of this invention, given by way of example, the oven may be an integral part of an assembly comprising the apparatus for agglomerating the coal or ore into balls. The finished products, before the agglomeration step, require a drying step which may be performed by circulating the product, prior to its agglomeration, through a bed of balls during the cooling thereof.

The oven according to this invention is characterised by many advantageous features of which some are listed herebelow:

The products are treated or processed continuously; The heating can take place very rapidly due to the very great gas-to-particles heat transfer surface area and to the solid-to-solid heat transfer;

The particularly simple method of recovering heat from the products being cooled;

The absence of difficulty in the recovery and combustion of volatile vapors from the distillation of the products or their binders, whereby the problem of atmospheric pollution is solved at the same time.

In conventional ovens designed for processing ball-shaped products (convection oven), the products are heated by circulating a gas through the bed. The heat transfers require the use of a very large volume of gas and are therefore attended by a considerable dilution of the gases released during the process, so that these gases are hardly recoverable, especially if they are of combustible nature.

Besides, since the continuously-vibrating grid supporting the products to be processed is at a substantially constant temperature, heat cycles detrimental to the stability of the products are safely avoided.

Of course, although the present invention has been described in conjunction with preferred embodiments, it is to be understood that modifications and variations may be resorted to without departing from the spirit and scope of the invention, as those skilled in the art will readily understand. Such modifications and variations are considered to be within the purview and scope of the invention and appended claims.

What is claimed is:

1. An oven for securing a heat transmission between a material of fine grain or sand and products in the form

of balls comprising an upper casing whose bottom is formed by a grill which carries the bed of products in the form of balls, hydraulic jacks giving to said grill variable accelerations, upper distributors distributing sand throughout the entire length of said bed of balls, funnels located under said grill for receiving said sand after traversing said bed of balls and said grill, a lower casing fed by said funnels and containing the sand in the form of a fluidized bed in which the sand is reheated and a particle conveyance located at the foot of each of said funnels for a pneumatic transport of the sand to said upper distributors.

2. An oven as set forth in claim 1 in which said grill is inclined to the horizontal and is formed of several successive elements.

3. An oven as set forth in claim 1 in which there are provided fixed scrapers whose fingers pass across the bars of said grill.

4. An oven as set forth in claim 1 wherein burners are submerged in said fluidized beds for heating the sand and a cyclone is provided for removing the fumes of said burners and rejecting it towards the exterior.

5. An oven according to claim 4 wherein baffles are provided in said fluidized beds for giving to said particles changes in direction allowing reheating the flux of the sand particles in a homogeneous way.

6. An oven as set forth in claim 1 wherein said particle conveyance is fed directly by the heated fumes of a burner in order to heat the sand.

7. An oven according to claim 1 wherein there is provided under said grill carrying said ball products a double play of perforated plates and means for sliding one upon the other in order to adjust the circulation flow of the sand across said ball products, said play of movable plates forming diaphragms actuated manually.

8. An oven according to claim 1 comprising for the return of the sand in diluted phase at the lower portion of each funnel a column provided at its foot with a means for receiving compressed gas, an electrical contact being provided in order to cut the feed of compressed gas when the level of sand in a funnel is too low.

9. An oven as set forth in claim 1 in which said fluidized beds define a fluidized loop for the circulation of said sand, said loop comprising a return channel provided at its end with an outlet and a stock tunnel receiving said sand, said oven comprising a tube for feeding said return channel and maintaining said fluidized beds at a constant level.

10. An oven according to claim 1 comprising a ventilator for sucking the combustible vapors coming from the thermic treatment of the products in the form of balls; a valve for adjusting the pressure in said oven at a value slightly above that of the exterior atmosphere and a conduit for evacuating said vapors and leading them to burners serving to heat the sand.

11. An oven according to claim 1 in which said upper casing comprises at each of its ends air tight bellows and said lower casing is a closed casing.

12. An oven as set forth in claim 1 in which the exterior tube of the funnels for the particles is provided with orifices for the escape of the fluidization gas of said fluidized beds.

13. An oven as set forth in claim 10 in which there is provided an adjusted flow of the fumes in order to facilitate the extraction of the combustible vapors.

14. An oven as set forth in claim 1 in which said fluidized beds and said funnels for the particles are fed by dust free fumes and without oxygen.

15. An oven as set forth in claim 1 in which a portion of the sand is heated to a high temperature and then mixed with the remainder.

16. An oven as set forth in claim 1 in which there are provided a plurality of zones, said zones respectively pre-heating said products in the form of balls, heating and cooling, with each zone recycling the sand coming from the fluidized beds.

17. An oven according to claim 4 in which said burners are fed by the gas products during the course of treatment.

18. An oven as set forth in claim 1, in which there is deposited upon the grill supporting the products in the form of balls when the latter during the course of treatment are fractured into a phase of plastic deformation, a metallic plate preventing all flow of sand upon a portion of said grill.
